UNITED STATES PATENT OFFICE.

DAVID MOXON, OF HOLYOKE, MASSACHUSETTS.

HOLDING AND DISPENSING DEVICE FOR PASTE-TUBES.

1,200,219.

Specification of Letters Patent.

Patented Oct. 3, 1916.

Application filed May 15, 1915. Serial No. 28,419.

To all whom it may concern:

Be it known that I, DAVID MOXON, a subject of the King of Great Britain, residing at Holyoke, in the county of Hampden and 5 State of Massachusetts, have invented certain new and useful Improvements in Holding and Dispensing Devices for Paste-Tubes, of which the following is a specification.

- 10 This invention contemplates an improved holding and dispensing device for paste tubes, being particularly designed for use as a device for holding tubes containing tooth paste.
- 15 The invention has as its primary object to provide a device of this character adapted to support a paste tube in convenient position so that a tooth brush may, at all times be readily placed beneath the mouth of the 20 tube to receive paste therefrom and wherein the device may be easily operated to expel paste from the tube.

A further object of the invention is to provide a device of this character adapted 25 to expel substantially all of the paste from the tube so that none of the paste will be wasted.

The invention has as a still further object 30 in this connection, to provide a device employing coacting rollers adapted to compress the tube for expelling the paste therefrom and wherein the free end of the tube will be thoroughly supported and guided to the said rollers.

35 The invention has as a still further object to provide a device of this character which may be conveniently suspended from a wall or other surface and which will furnish a neat and attractive article adapted to also 40 provide a tooth brush rack. And the invention has as a still further object to provide a device of this character wherein the body portion thereof will be formed of few and simple parts and wherein the means employed for manipulating the paste tube will 45 also be of exceedingly simple character.

Other and incidental objects will appear 50 as the description proceeds and in the drawings wherein I have illustrated the preferred embodiment of the invention and 55 wherein similar reference characters designate corresponding parts throughout the several views. Figure 1 is a front elevation of my improved device showing tooth brushes arranged thereon and illustrating the conventional type of paste tube sus-

pended from the device. Fig. 2 is a side elevation showing the mating rollers adapted to compress the paste tube. Fig. 3 is a vertical sectional view more particularly 60 showing the detail construction of the device. Fig. 4 is a transverse section taken on the line 4—4 of Fig. 3 and more particularly showing the arrangement of guide flanges for the paste tube, and Fig. 5 is a 65 perspective view showing the tube receiving support of the device detached.

In carrying out my invention, I employ a base 10 which is preferably formed from a single piece of suitable sheet metal rolled 70 to provide a marginal flange 11. The base 10, adjacent the upper extremity thereof, is provided with a preferably circular opening surrounded by a laterally directed flange 12 and secured to the rear side of the base 75 and projecting into the said opening are a plurality of yieldable tongues 13 adapted to engage a looking glass 14 seating against the flange. In use, it is intended that the device be suspended from a wall or any other 80 suitable character of support and the base 10 is, at the upper end thereof, accordingly provided with an opening 15 adapted to receive a suspension device.

Connected to the base 10 adjacent opposite 85 sides thereof and substantially midway the ends of the base, are pairs of coacting yieldable fingers 16 each adapted to detachably receive and support a tooth brush in the manner shown in Fig. 1 of the drawings, the 90 said tooth brushes having been conventionally illustrated. By this construction, it will be observed that my improved device may be employed as a tooth brush rack.

Arranged medially upon the base 10 and 95 extending longitudinally thereof is a support 17 shown in detail in Fig. 5 of the drawings. This support is preferably formed from a single piece of suitable sheet metal bent intermediate its ends to provide 100 substantially parallel side walls 18 which are secured at their free edges in any suitable manner to the base 10, as shown in Fig. 4 of the drawings.

The side walls 18 are joined by a substantially straight connecting portion 19 which, throughout the major portion of its length is longitudinally split to provide coacting arcuate flanges 20 as will be best observed upon reference to Fig. 4 of the drawings. 110 The flanges 20 are arranged to curve laterally and inwardly toward the base 10 to de-

fine an intermediate substantially semi-circular channel or guide way, while the inner free ends of the said flanges are disposed in spaced relation to define a slot 21 extending 5 longitudinally of the support and opening through the lower end thereof. Fitting over the upper end of the support is a closure cap 22 which is detachably held in position by side flanges 23.

10 Mounted upon the support 17 adjacent the upper extremity of the guide way thereof is a tube compression mechanism. This mechanism includes coacting rollers 24 which are preferably formed of suitable resilient 15 material and are arranged to normally engage each other. The rollers 24 are mounted upon substantially parallel shafts 25 journaled in the side walls 18 and which are each preferably screw threaded at one extremity to receive a nut 26 as shown in Fig. 20 1 of the drawings for holding the said shafts in position.

Keyed upon the shafts 25 at one side of the support are intermeshing pinions 27 and 25 arranged to coact with one of said pinions, is a pawl 28 pivotally supported upon the adjacent wall of the support. One of the shafts 27 is extended at one extremity thereof and is provided with an operating 30 knob 29, and it will now be observed that when the said knob is turned, rotary motion thus imparted to one of the rollers 24 will be communicated to the other roller through the medium of the pinions 27 while the pawl 35 28 is adapted to prevent any retrograde movement of the said rollers.

Suitably connected to the upper terminals of the flanges 20 is a longitudinally extending guide member 30 which projects upwardly toward the cap 22 as well as rearwardly toward the base 10 as more particularly shown in Fig. 3 of the drawings. This guide member is preferably formed from a strip of suitable resilient sheet metal 40 and adjacent the upper extremity thereof, is bent longitudinally to provide an arcuate terminal 31 curving laterally and forwardly in the direction of the rollers 24 in upward spaced relation thereto.

50 Secured at one extremity to the base 10 at a point substantially midway the ends of the guide member 30 is a second guide member 32 arranged to coact therewith. This guide member 32 is also preferably formed 55 from a strip of suitable resilient sheet metal and is longitudinally curved intermediate its ends to extend over the arcuate extremity 31 of the guide member 30 in substantially concentric spaced relation thereto, it being understood, of course, that the guide 32 is arranged over the guide 30. At its outer extremity, the guide 32 is arranged to extend forwardly over the rollers 24 in spaced 60 relation thereto and at its outer end, is reversely curved to provide a substantially 65

arcuate terminal 33 with the convex side thereof presented toward the rollers 24.

It will now be observed that the rollers 24 are housed within the upper portion of the support 17 and are disposed at the inner upper end of the guide-way provided by the flanges 20. In the drawings, I have shown the manner in which a conventional type of paste tube is connected with the device, in order that the operation of the invention 70 might be entirely clear. The paste tube is laid within the guide-way of the support to rest upon the flanges 20 and the inner end of the tube is then engaged between the rollers 24 by turning the knob 29. When so 80 engaged, it will be noted as particularly shown in Fig. 1 of the drawings, that the mouth of the tube will be disposed in alignment with the slot 21 so that a tooth brush may be readily inserted within the slot and 85 moved to a position to receive paste issuing from the tube. When it is desired to expel the paste from the tube, the knob 29 is then further operated to compress the tube when the tube will be drawn upwardly between 90 the rollers 24 and since the slot 21 extends throughout the length of the flanges 20, it will be seen that a tooth brush may, at all times be readily disposed beneath the mouth of the tube. As the tube is thus compressed 95 in use, the inner extremity thereof will be directed upwardly within the upper portion of the support 17 to strike the free convex terminal 33 of the guide member 32. This guide member will then direct the inner end 100 of the tube as the tube is fed from the rollers 24 laterally toward the base 10 between the said guide member and the guide member 30 to move freely through the arcuate guide way defined thereby. As shown in 105 Fig. 3, the guide member 30 is adapted to support the inner extremity of the tube, so that it will be prevented from curling up within the support to impede the operation of the rollers 24 and will be housed within 110 the said support so that the device, in use, will present a neat and attractive appearance.

Attention is particularly directed to the fact that the rollers 24 are adapted to operate upon the tube as more particularly shown in Fig. 3 of the drawings substantially throughout the entire length of the tube, so that all of the paste may be expelled therefrom. This is obviously a feature of advantage since, in use, none of the paste will be wasted.

Having thus described my invention, what I claim and desire to secure by Letters Patent is:—

1. A device of the character described including a base, a support arranged thereon, substantially arcuate coacting flanges carried by the support and providing a guide-way, compression mechanism mounted upon 115

- the support at one end of said guideway, and coacting guide members arranged adjacent said mechanism, said guide members being carried one by the said flanges and 5 the other by the base, the said mechanism being adapted to engage a paste tube disposed in said guideway to direct the inner end of the tube toward the said guide members and the said guide members being 10 adapted to direct the inner end of the tube laterally upon one side of said rollers.
2. A device of the character described including a support providing a guideway, and compression mechanism arranged adjacent 15 the upper end of said guideway, the said mechanism being adapted to engage a paste tube freely depending from said mechanism in front of the guideway with the guideway adapted to provide a support for 20 the tube.
3. A device of the character described including a support having spaced flanges formed thereon adapted to receive a tooth brush therebetween, and compression mechanism carried by the support, the said mechanism being adapted to engage a paste tube resting against said flanges with the mouth 25 of the tube disposed opposite the space between the flanges.
- 30 4. A device of the character described including a support formed to provide a guideway having a longitudinally extending slot formed therein adapted to receive a tooth brush, and compression mechanism carried by the support, the said mechanism being adapted to engage a paste tube disposed in said guideway with the mouth 35 of the tube arranged opposite said slot.
5. A device of the character described including a support having side walls joined 40 by a connecting portion, the connecting portion being split for a portion of its length and bent to provide a guideway with the said split adapted to receive a tooth brush, and compression mechanism mounted upon 45 said side walls of the support and adapted to engage a paste tube disposed against said guideway for moving the mouth of the tube longitudinally of the said split as the paste is expelled from the tube by the said rollers. 50
6. A device of the character described including a support, compression mechanism carried by the support, and spaced superposed guide members arranged adjacent said mechanism, the said mechanism being 55 adapted to engage a paste tube resting against the support and said members being adapted to coact to direct the inner end of the tube therebetween with one of the members adapted to support the inner extremity of the tube.
7. A device of the character described including a support, compression mechanism carried thereby, and coacting guide members mounted adjacent said mechanism, 65 the said mechanism being adapted to engage a paste tube resting against said support with one of the said guide members adapted to engage the inner extremity of the tube for directing it to a position to be supported 70 by the other of said guide members.
8. A device of the character described including a support provided with spaced members adapted to receive a tooth brush therebetween, a compression mechanism 75 mounted to overhang the said members adjacent one extremity of the support and adapted to engage a paste tube resting against said members for moving the mouth of the tube longitudinally of the space between the members as the paste is expelled 80 from the tube.

In testimony whereof I affix my signature.
DAVID MOXON. [L. s.]
